UNITED STATES PATENT OFFICE

2,092,139

STOCK TANK HEATER

Tobias Ramer, Elkhart County, Ind.

Application March 21, 1936, Serial No. 70,150

5 Claims. (Cl. 126—360)

My invention relates to water heaters, and particularly to stock tank heaters.

The principal object of my invention is to provide an improved, simplified, and durable stock tank heater for heating the drinking water supplied to farm live stock, although it may be employed for other suitable purposes.

Another object of the invention is to provide a stock tank water heater of novel sheet metal construction in which the heater body is composed of a horizontal heater, or burner, section and an inclined section connected therewith, the latter having a separate air conduit therein for supplying air to the burner.

15 A third object is to provide a stock tank heater of novel sheet metal construction in which the heater body is composed of a horizontal heater, or burner, section and an inclined section connected therewith, the former being made of three pieces of sheet metal and the latter having a two part separate air conduit unit removably mounted therein for supplying air to the burner.

20 Other and more specific objects of the invention are mentioned and described herein.

25 The invention is illustrated in the accompanying drawing, wherein

Figure 1 illustrates my improved tank heater arranged in a water tank;

Figure 2 illustrates a longitudinal section taken 30 through the heater unit, very much enlarged;

Figure 3 illustrates a section taken on line 3—3 of Figure 2;

Figure 4 illustrates a sectional view of the check valve for the fuel supply pipe; and

35 Figure 5 illustrates a section taken on line 5—5 of Figure 2, omitting the bottom wall of the heater body.

Similar numerals of reference indicate like parts throughout the several views on the drawing.

40 Referring to the details of the drawing the numeral 1 indicates a stock water tank within which my improved stock tank heater is removably arranged. The body of my improved tank heater, which may be rectangular in cross section, and which preferably is made of sheet metal, may comprise the heater, or burner casing section 2 and the inclined air conduit casing section 3, the latter being upwardly inclined to project above the surface of the water contained in the tank 1.

45 The heater body, as illustrated, is preferably made from three pieces of sheet metal 4, 5, and 6, respectively, in which construction the piece or part 4 is formed trough-like, or channelled,

and bent at 7 to provide the bottom wall 8 and opposed side walls 9 and 10 of the body section 3, and providing also bottom wall 11 and side walls 12 and 13 (one only being shown) of the burner casing section 2.

5 In this construction the side walls 12 and 13 are extensions of the side walls 9 and 10, respectively, and the bottom wall 11 forms an integral extension of the angular bottom wall 8. The heater body piece 5, which is bent at 14, 10 constitutes the top wall for both casing sections 2 and 3 and has its marginal edges welded, or otherwise secured, to the upper edges of the side walls 9 and 10 of body casing 3 and also to the side walls 12 and 13 of the body casing section 2. 15

The sheet metal piece or part 6 forms the end wall for the burner casing section 2 and has its marginal edges welded, or otherwise secured, to the adjacent side walls 12 and 13, bottom wall 11 and top wall 5 of the burner casing section, 20 whereby a watertight body unit is produced. The numeral 15 indicates a plurality of transverse water circulating flues terminally secured in the side walls 11 and 12 of the casing section 2 to conduct water therethrough. A vent pipe 25 or chimney 16 may be mounted upon the burner casing 2 over a suitable opening to place the interior of said casing in communication with the outer atmosphere.

The numeral 17 indicates an inverted trough-like, or channelled, air conduit removably arranged within the body casing 3 and upon the bottom wall 11 thereof, the lower end of said air conduit cooperating with the open end of the inverted air conduit 18 which is arranged removably within the casing section 2 and upon the bottom wall thereof. One end 19 of the conduit section 18 is permanently closed. Preferably, there is effected a telescopic sliding connection between the conduit members 17 and 18 to 30 facilitate the passage of air therethrough to the burner hereinafter mentioned, such telescopic connection being facilitated by a guide finger 20 mounted upon the lower end of the conduit member 17. 35

A pair of opposed angle iron guide and retainer pieces 21 are secured to the side walls 9 and 10 to maintain the juxtaposition of the conduit member 17. A fixed stop element 22 may engage the end wall of conduit member 18 to maintain 50 the latter against longitudinal displacement and in the proper relation with the conduit member 17.

The top wall of the conduit member 18 is provided with an air outlet opening 23 to conduct air 55

supply to the liquid fuel burner 24 which is carried by the elbowed fuel supply pipe 25 which is connected with a ball check valve 26. Numeral 27 indicates a fuel supply elbow connected with the valve 26, said elbow being provided with a pair of opposed brackets 28 which are rigidly fastened to the top wall of conduit member 18 by the bolts 29, (Fig. 5), whereby the burner unit 24 and valve 26 are supported and maintained in operative position in relation to the flues 15.

The numeral 30 indicates an arcuate air baffle mounted upon the conduit 18 adjacent the opening 23 to facilitate the direction of air to the burner 24. A fuel supply pipe 31 is connected with the elbow 27 to supply liquid fuel to the burner from a container 32 which may be under the control of a needle valve 33. The upper end of the air conduit 17 may be permanently open, and a cover 34 hinged at 35 may function to close 20 the remaining open end of the casing section 3.

I claim:

1. A stock tank heater comprising a burner casing section, an inclined air conduit casing section permanently connected therewith, said burner casing section having a plurality of water circulating flues mounted therein, a two part air conduit removably arranged within the burner casing and air conduit casing sections, the outer part of said air conduit comprising an inverted 25 channelled member, a liquid fuel burner mounted within said burner casing section, means for supplying liquid fuel to said burner, a vent pipe for said burner casing section, and a closure for the upper end of said air conduit casing section.
- 35 2. A stock tank heater comprising permanently connected burner casing and air conduit casing sections forming a heater body, said body being formed from three pieces or parts of sheet metal, of which the main part is trough-like in formation to provide bottom and side walls for said two casing sections, the other two parts of said body forming the top wall for both of said casing sections and the end wall for said burner casing

section, a plurality of water circulating flues mounted in the burner casing section, a liquid fuel burner mounted within said burner casing section relatively to said flues, means for supplying air to said burner, and means for supplying liquid fuel to said burner.

5 3. A stock tank heater comprising a burner casing section, an inclined hollow casing section connected therewith, a separate air conduit section arranged within said inclined section and extending into said burner casing section along the bottom wall of the latter, a liquid fuel burner mounted upon the lower end of said air conduit and adapted to receive a supply of air from said air conduit.

10 4. A stock tank heater comprising a burner casing section, an inclined hollow casing section connected therewith, a separate channelled air conduit section arranged within said inclined and burner casing sections and upon the bottom wall 20 of the latter, said air conduit being provided with an air outlet opening, a liquid fuel burner mounted upon the lower portion of said air conduit adjacent said air outlet opening, and a plurality of transverse water circulating flues 25 mounted in said burner casing section.

15 5. A stock tank heater comprising a burner casing section, an inclined hollow casing section connected therewith, said burner casing section having a plurality of water circulating flues mounted 30 therein, a two part channelled air conduit removably arranged within said burner and inclined casing sections, one part of said air conduit being arranged upon the bottom wall of said burner casing section and provided with an air outlet, a 35 liquid fuel burner mounted upon said air conduit section which is provided with the air outlet and adjacent the latter, said fuel burner being removable with said air conduit, a plurality of water circulating flues mounted in said burner casing section, and means for supplying liquid fuel to 40 said burner.

TOBIAS RAMER.
